UNITED STATES PATENT OFFICE

2,630,910

MATERIAL SHEDDER FOR DRAWBENCH TONGS

Ralph R. Turner, Warwick, R. I., assignor to
United Wire & Supply Corporation, a corpora-
tion of Rhode Island

Application June 15, 1948, Serial No. 33,121

2 Claims. (Cl. 205—3)

1

This invention relates to a draw bench and more particularly to the discharge of the work from the draw bench.

When drawing tubing, wire, or rod, a certain amount of elasticity or tension is set up in the material being drawn which expends itself when the material leaves the die, causing the tube, wire, or rod to snap forward and strike the draw carriage or tongs. The sudden shock of abruptly stopping the material being drawn causes it to kink or bend or twist out of shape. The amount of spring tension set up in the work is in direct proportion to a multiple of the reduction of the cross section area and the length. The problem of kinked, bent, or twisted material becomes more acute with double and triple drawing as the gripper carriage is heavier and will not run away when it receives the shock of the expending material being drawn, which in turn causes it to kink more than with a single draw.

Shock absorbers have been utilized on the gripper carriage or tongs with little avail, as they cannot absorb all of the shock which is present at the time of release of the work from the die.

One of the objects of this invention is to provide a method which will allow the material being drawn to extract itself from the tongs or carriage and expend its pent-up energy in a raceway along the side of the draw bench or on a table, should it be applied to the overhung type of draw bench.

Another object of this invention is to provide a deflector carried by the carriage or tongs which will direct the material into the raceway in such a manner that it will prevent kinking or bending of the material when it springs forward out of the gripper or tongs.

Another object of this invention is to dispense with or to reduce the number of unloading arms which have heretofore been required and which present a substantial maintenance factor.

Another object of the invention is to eliminate all of the scrap and disadvantages in redrawing, stacking the work, and other hazards which come from crooked material.

With these and other objects in view, the invention consists of certain novel features of construction, as will be more fully described and particularly pointed out in the appended claims.

In the accompanying drawings:

Figure 1 is an elevation showing a draw bench with a carriage equipped with the deflector for downwardly discharging the work;

Figure 2 is a sectional view of a fragmental portion showing the discharge deflector;

Figure 3 is a perspective view of the discharge deflector;

Figure 4 is a section on line 4—4 of Figure 2;

Figure 5 is a sectional view on line 5—5 of Figure 1;

Figure 6 is a perspective view of a chute for side ejection carriage;

Figure 7 is an elevation of a modified form of

2

draw bench showing an upward ejection type carriage;

Figure 8 is a fragmental elevation showing the continuation of the draw bench in the provision of a raceway beyond the end thereof for receiving the drawn material;

Figure 9 is a section looking down on top of the carriage of Figure 7; and

Figure 10 is a perspective view of the deflector shown in Figure 7.

In proceeding with this invention, I provide a long raceway generally parallel, but at one side of the path of work which extends beyond the end of the point of draw of the material being drawn a distance usually about the length of the material being drawn so that the tension in the material may expend itself by forcing the material the required distance to dissipate the tension therein, and I then provide upon the carriage or tongs a deflector or chute for directing the material into this raceway. By this arrangement the material does not come up against any abrupt obstruction and cause a bending or twisting of the end portion of the material. The deflector usually consists of walls which are generally at an angle of forty-five degrees to the length of the machine for directing the end of the material to the raceway along which it will expend its force. Suitable guides are provided for controlling the material as it expends its energy in moving itself along the raceway.

With reference to the drawings, 10 designates generally the usual draw bench having a carriage 11 thereon along one side of the draw bench, and 35 extending a substantial distance beyond the draw bench and substantially of the same length as the draw bench, there is a raceway designated generally 12. This raceway may be a trough along one side of the carriage, or it may be a table or 40 any other suitable form.

Provided upon the carriage there will be a deflector or chute which is designated generally 13, but which may take various forms depending upon the type of jaws which are used in the carriage for gripping the material. Thus, I may provide the type which is utilized for the ejection of the material from the bottom of the jaws, as I have shown in Figures 1 to 5, or the chute may be of a more complex construction, such as shown 45 at 14 in Figure 6, where the jaws are of the side ejection type, or as shown at 15 in Figure 10 where the jaws are of the top ejection type.

In the showing in Figures 1 to 5 the gripper head 16 is mounted upon the carriage 11 which 55 is driven by a motor 18 engaging the racks 17 on either side of the carriage. The head 16 is of the bottom discharge type and comprises in this instance an arrangement for gripping three workpieces at one time. The gripping arrangement is identical in each of the three and 60 comprises a fixed jaw 20 and a movable jaw 21 which is keyed to a shaft 22, which shaft has a gear at its upper end which is operated by a rack 24

having a plunger rod 25 to engage the support 26 for the die 27 through which one end of the work 28 projects to be gripped by the jaws 20 and 21. The movement of the rack will rotate the movable jaw 21 into engagement with the work 28 so as to swing this jaw into gripping engagement therewith, after which, the movement of the carriage to the right, as shown in Figure 1, will tend to force the movable jaw 21 further into engagement with the work and hold the same firmly between the jaws. After the work is drawn through the die 27, the spring of the work forwardly will swing the jaw 21 clockwise, as shown in Figure 4, to release it from engagement with the work, whereupon the work will jump longitudinally forwardly as it is released from the gripper head.

In order to guide this work out of the carriage and allow it to expend its energy, I provide the deflector or chute which is designated generally 13 and shown in perspective in Figure 3 which comprises essentially a baffle plate 30 of a width to be comparable to the gripper head and the work accommodated. By means of extensions 31, this plate is positioned into the path of movement of the work 28 as it jumps forwardly upon release of the gripper jaws. This plate is mounted upon the gripper head by means of ears 32 which are deflected from the plate and provided with openings 33 to receive screws 34 for holding it in position on the support 35 of the gripper head. Suitable flanges 36 are formed on the edges of the plate so as to prevent any lateral movement. This plate serves to deflect the stock downwardly, as shown in dot and dash lines at 28' in Figure 1 and Figure 2, so that the work will engage the inclined directing portion 37 (Figure 5) of the raceway to be further directed into the portion 38 thereof which has a retaining rail 39 flanged inwardly as at 40. This formation 37, 38, 39, and 40 forms the raceway 12 which extends a substantial length beyond the end of the point of release of the work from the carriage so that the work will shoot down this raceway to expend its energy without coming against any restraining abutment which would tend to bend or twist the ends of the work.

In some cases instead of the gripper head being of the bottom discharge type, the gripper head may be one of the side discharge types in which instead of using the chute or deflector 13 of Figure 3, a deflector chute 41, as shown in Figure 6, would be used in which there is a baffle plate 41 with its extending portion 42 and mounting ears 43 having openings 44 for securing it in position. In this case the work will be guided along the plate 41 to direct the same sideways of the machine and along the horizontal surface 45 and beneath the surface 46 until it reaches a location clear of the draw bench where the plate 45 is flanged downwardly by reason of the vertical wall 47 which with the vertical wall 48 extending from wall 46 serves to direct the work downwardly, the combining effect of these walls being to direct the work from the side discharge jaws outwardly and then downwardly onto the raceway 12 to allow the same to expend its energy.

In the showings in Figures 7 through 10 a draw bench 10' of the type having a chain 50 is illustrated in which the carriage 11' has a hook 51 to engage this chain for movement along the draw bench. In this case the gripper head is similar to the gripper head described in connection with Figures 1 to 5 and is designated 52 which has a single acting jaw constructed sub-

stantially as the gripper described in connection with Figures 1 to 5. This gripper, however, is of the upward discharge type and, accordingly, a differently constructed chute or deflector is provided. The gripper, in this case, has a fixed jaw 53 with a movable jaw 54 mounted upon a rotating shaft 55 which carries a gear 56 to engage the rack 57 and be operated by the plunger 58 which engages the support 26 for the die 27, the work 28 being moved between the jaws 53 and 54 to be gripped and forced further into engagement by reason of the pull on the chain 50 with which the hook 51 engages. As the work is finally pulled through the die 27, it will jump forwardly and releases itself from the jaws, whereupon the chute 15 (Figure 10) which is fastened to the gripper head by reason of ears 61 having openings 62, will engage the portion 60 of the chute or deflector to direct the work upwardly, thence along the horizontal portion 63 and against the inclined guide 64 beneath the horizontal portion 65 to cause the work to be moved laterally of the draw bench until it comes opposite the opening 66 formed by a downwardly extending portion 67 from the plate 63 and the downwardly extending portion 68 from the portion 65, thus causing the work to be discharged onto the bottom wall 69 of the raceway and directed along the raceway designated 12, as shown in Figure 8.

From the above, it will appear that I have provided a raceway into which the work is discharged by means of a chute so that the work may expend such energy as it has without coming abruptly against any portion which might tend to bend it or distort its end.

I claim:

1. In a draw bench, a die, a draw carriage including tongs for drawing the work through the die, said tongs having jaws opening to permit partial endwise passage of the work tube and lateral movement thereof out of the jaws, a way extending generally lengthwise of the bench located laterally of and in close proximity to the path of the work being drawn and extending beyond the end position of the tongs at the completion of the draw, and a deflector carried by the tongs having a surface located beyond the forward end of the work and in axial alignment therewith and at such an angle thereto as to engage the end of the work as it is moved through the jaws under kinetic energy at the completion of the draw to direct the work out of the tongs and guide it into the way for movement therealong to expend its kinetic energy.
2. In a draw bench as in claim 1 wherein the deflector comprises one wall at an angle to the longitudinal extent of the bench to direct the work laterally thereof out of the tongs and a second wall at a different angle to the longitudinal extent of the bench and so positioned as to direct the work into the raceway.

RALPH R. TURNER.
